UNITED STATES PATENT OFFICE.

THOMAS L. BURTON, OF ST. LOUIS, MISSOURI, ASSIGNOR TO THE AMERICAN BRAKE COMPANY, OF ST. LOUIS, MISSOURI, A CORPORATION OF MISSOURI.

BRAKE-BEAM SUSPENSION.

1,261,487.

Specification of Letters Patent. Patented Apr. 2, 1918.

Application filed June 30, 1917. Serial No. 177,999.

To all whom it may concern:

Be it known that I, THOMAS L. BURTON, a citizen of the United States, residing at St. Louis, in the State of Missouri, have invented a certain new and useful Improvement in Brake-Beam Suspensions, of which improvement the following is a specification.

This invention relates to suspension means for brake beams for railway cars, and more particularly to that form of brake beam in which the brake shoes are pivoted upon trunnions at the opposite ends of the beam, one of the objects being to provide improved means for maintaining the beam in a substantially parallel relation as the brake beam and shoe are moved toward the wheel in the application movement and away from the same during the release action whereby the shoe will remain substantially concentric to the wheel under the various conditions of wear of the brake shoe and the wheel.

It has heretofore been proposed to provide in addition to the two hangers at the ends of the beam, an intermediate or central hanger pivotally connected to a bracket on the frame and to a special jaw at the middle portion of the beam, and my improvement comprises an improved form of additional hanger rigidly supported on the frame, and coöoperating with a curved plate or tongue on the brake beam, which may be located at the middle or other intermediate portion of the beam.

In the accompanying drawing, Figure 1 is a side elevation of a brake beam suspension embodying my improvement;

Fig. 2 an end elevation showing a portion of the brake beam in section; and

Fig. 3, a half plan of the beam with the additional hanger shown in horizontal section.

According to the construction shown in the drawing, the brake beam 10, is provided with trunnions 11, at its ends, on which are pivotally mounted the brake heads 13. The usual hangers 12, pivotally connected to the brake beam or brake head and to the truck frame, serve as a support for the same and permit a free swinging movement.

Where the usual type of clasp brake rigging is employed, with two sets of truck levers and rods one on each side of the truck, such as truck levers 14, and rods 15 and 16, which parts are duplicated at each side of each pair of wheels, the brake beams are provided with rigidly connected jaws 20, for pivotal connection with the lower ends of said truck levers, as will be readily understood.

In accordance with my improvement an additional hanger plate 17, is rigidly secured to a bracket 21, on the truck frame, said plate being provided with a bifurcated lower end, preferably by riveting thereto the piece 17^a, with the spacing rivets 22, and 19, separated a given distance to act as a guide for the curved tongue or plate 18 rigidly secured to the brake beam 10. The tongue 18, is curved on such an arc as to coöperate with the radius of the hanger links 12, and maintain the brake beam substantially concentric with the wheel during its application and release movements.

The additional hanger may be located at the middle of the brake beam or two of such hangers may be located at other intermediate points at either side of the center if preferred.

This additional rigid hanger and curved tongue plate also have the advantage of giving a more secure support for the brake rigging and at the same time may be used in many truck designs where a pivoted link is inapplicable.

Having now described my invention, what I claim as new and desire to secure by Letters Patent is:

1. In a brake device, the combination with a brake beam having hanger links at its opposite ends, of a hanger plate rigidly supported on the frame and provided with a guide opening at its lower end, and a curved tongue rigidly secured to the brake beam and extending through said guide opening.

2. In a brake device, the combination with a brake beam having hanger links at its opposite ends, of a hanger plate rigidly supported on the frame and provided with a

bifurcated lower end and guide pins, and a curved tongue rigidly secured to the brake beam and extending between said guide pins.

3. In a brake device, the combination of 5 a brake beam having hangers at its opposite ends and provided with jaws, two sets of truck brake levers, one at each side of the truck, pivotally connected with said jaws,

a hanger plate rigidly supported on the frame and provided with a guide opening 10 at its lower end, and a curved tongue rigidly secured to the brake beam between said jaws and extending through said guide opening.

In testimony whereof I have hereunto set my hand.

THOMAS L. BURTON.
